(57) **CLAIM**

The ornamental design for an adjustable shopping cart handle with latch, as shown and described.

DESCRIPTION

FIG. 1 is a top, left, front, isometric view showing an adjustable shopping cart handle with latch of my new design in an intermediate position.

FIG. 2 is a front view of the adjustable shopping cart handle with latch of FIG. 1.

FIG. 3 is a back view of the adjustable shopping cart handle with latch of FIG. 1.

FIG. 4 is a left side view of the adjustable shopping cart handle with latch of FIG. 1. The right side view is a mirror image of this left side view.

FIG. 5 is a top view of the adjustable shopping cart handle with latch of FIG. 1.

FIG. 6 is a bottom view of the adjustable shopping cart handle with latch of FIG. 1.

FIG. 7 is a top, left, front, isometric view showing the adjustable shopping cart handle with latch of FIG. 1 but in a fully collapsed position.

FIG. 8 is a top, left, front, isometric view showing the adjustable shopping cart handle with latch of FIG. 1 and FIG. 7 but in a fully extended position.

FIG. 9 is a detailed view of the latch taken from line 9 in FIG. 8; and,

FIG. 10 is a right side view of the adjustable shopping cart handle with latch shown in condition of use.

The broken lines in the drawings depict portions of the adjustable shopping cart handle with latch that form no part of the claimed design. The dot-dash broken line in FIGS. 8 and 9 depict enlarged portions and form no part of the claimed design. The broken line showing of the shopping cart in FIG. 10 depicts environment that forms no part of the claimed design.

1 Claim, 8 Drawing Sheets
